UNITED STATES PATENT OFFICE.

GEORGE W. WHITEHURST AND FEATHERSTON BRADSHAW, OF ELLISVILLE, MISSISSIPPI.

PLOW-STOCK.

No. 830,390.

Specification of Letters Patent.

Patented Sept. 4, 1906.

Application filed April 19, 1906. Serial No. 312,602.

To all whom it may concern:

Be it known that we, GEORGE W. WHITEHURST and FEATHERSTON BRADSHAW, citizens of the United States, residing at Ellisville, in the county of Jones and State of Mississippi, have invented certain new and useful Improvements in Plow-Stocks; and we do declare the following to be a full, clear, and exact description of the invention, such as will enable others skilled in the art to which it appertains to make and use the same.

This invention relates to improvements in plow-stocks.

15 The object of the invention is to provide a plow-stock having an adjustable beam whereby the draft on the plow may be varied.

A further object is to provide a stock having an adjustably-connected beam on the forward end of which is formed a clevis, whereby additional draft adjustment may be had and whereby means is provided for supporting a colter-blade.

25 With the above and other objects in view the invention consists of certain novel features of construction, combination, and arrangement of devices hereinafter described and claimed.

30 In the accompanying drawings, Figure 1 is a side view of a plow having a stock constructed in accordance with the invention, showing in full and dotted lines the normal and adjusted positions of the plow-beam.

35 Fig. 2 is a perspective view of the stock, showing the parts of the same detached. Fig. 3 is a top plan view of the stock, and Fig. 4 is a detail horizontal sectional view through the connected ends of the beam and stand-

ard.

40 Referring more particularly to the drawings, 1 denotes the plow-stock, which consists of the beam 2 and the standard 3, the latter being curved downwardly and provided with an elongated hole or slot to receive a bolt 4, by means of which the blade or shovel 5 of the plow may be attached thereto. Connected to the stock 1 are suitable handles 6, by which the plow is held.

45 The rear end of the beam 2 is offset, as shown at 7, thereby forming a shoulder 8. The inner end of the offset portion of the beam is increased in width and provided with a series of bolt-holes 9. The beam ad-

jacent to the offset portion 7 is provided with 55 a bolt-hole 10.

The forward end of the standard 3 is cut away or recessed on one side, as shown at 12, and with said recessed portion of the standard is adapted to be engaged the offset end 7 of the beam, said beam being pivotally connected with the standard by means of a bolt 13, which is passed through the hole 10 in the beam and through an alined hole 14, formed in the reduced end of the standard. 65 By means of a bolt 14', passed through one of the holes 9 in the end of the beam and a hole 15 in the standard, said beam may be held in an upwardly or downwardly projecting inclined position, thereby providing for 70 an adjustment of the draft.

In the space formed by the shoulder 8 of the offset portion 7 of the beam and a shoulder formed in the reduced end of the standard is adapted to be supported a cutting-blade 75 or colter 16. On the outer end of the beam is arranged a clevis 17, said clevis being preferably formed by bending the end of the beam into the desired shape and forming a series of apertures 18 therethrough, with one 80 of which is adapted to be connected the draft devices of the plow, thereby providing for the further adjustment of the draft.

A plow-stock constructed as herein shown and described will be simple, strong, durable, and inexpensive in construction, efficient in operation, and well adapted to the purpose for which it is designed.

From the foregoing description, taken in connection with the accompanying drawings, the construction and operation of the invention will be readily understood without requiring a more extended explanation.

Various changes in the form, proportion, and the minor details of construction may be 95 resorted to without departing from the principle or sacrificing any of the advantages of this invention as defined by the appended claims.

Having thus described our invention, what 100 we claim as new, and desire to secure by Letters Patent, is—

1. A plow-stock comprising a standard, a beam pivotally and adjustably connected thereto, said beam having in its end a series 105 of bolt-holes adapted to be brought into alignment with a bolt-hole in said standard, a bolt for vertically adjusting said beam, offsets in

the beam and standard, and a clevis formed on the forward end of said beam, substantially as described.

2. A plow-stock comprising a standard having a recessed upper end, a beam having an offset rear end to engage the recessed end of said standard, shoulders formed in the recessed offset ends of said standard and beam a colter-blade supported in said shouldered recesses, a bolt to pivotally connect said beam and standard, said beam having in its end a series of bolt-holes, adapted to be brought into alinement with a bolt-hole in

said standard, a bolt adapted to be inserted through said alined apertures to hold said beam in its adjusted positions, and a clevis formed on the outer end of said beam, substantially as described.

In testimony whereof we have hereunto set our hands in presence of two subscribing witnesses.

GEORGE W. WHITEHURST.
FEATHERSTON BRADSHAW.
